UNITED STATES PATENT OFFICE

LINDSAY THORNE CRABBE, OF CHICAGO, ILLINOIS, ASSIGNOR TO PHOENIX-HERMETIC COMPANY, OF BROOKLYN, NEW YORK, A CORPORATION OF NEW YORK

JAR CLOSURE

Application filed August 16, 1929. Serial No. 386,322.

The invention relates to new and useful improvements in jar closures, and more particularly to a jar closure which includes a cap and retaining band.

5 An object of the invention is to provide a retaining band the ends of which are connected so that the band may be easily opened, in which the connection for the ends of the band is so constructed that when once connected and the closure sealed to the jar, it 10 cannot be readily separated without destroying the connection.

In the drawing:—

Fig. 1 is a side view showing a portion 15 of a jar with my improved closure applied thereto.

Fig. 2 is a view showing the ends of the band as initially formed.

Fig. 3 is a view of the end of the band having the retaining lug, with the lug shaped 20 for insertion through the slot in the other end of the band.

Fig. 4 is a view showing the ends of the band joined and the retaining lug bent so as 25 to lock the parts together.

The invention is directed to a jar closure of the type wherein the cap is secured to a jar by a retaining band. The retaining band is formed from a strip, the upper edge portion 30 of which is turned at an angle so as to overlie the cap and the under edge of the band is turned beneath a shoulder on the jar for securing the cap in sealed contact with the lip of the jar. The invention is directed particularly to the means for joining the ends of 35 a band of this type. It has been a common expedient to provide one end of a band with a projecting lapped tongue which has a slot therethrough and the other end of a band 40 with a locking lug which projects through said slot and is adapted to be folded down to hold the ends of the band together. It is very easy to lift the tongue, thus raising the lug so as to separate the ends and remove the 45 cap from the jar and then apply the cap and bend the tongue and lug back into their initial position, thus reclosing the jar.

The present invention has to do with the particular shaping of the locking lug which 50 prevents the opening of the band and tamper-

ing with the contents of the jar. To this end the locking lug is so formed that the metal of the lug must be bent longitudinally before it can be inserted through the slot after which it is flattened so that portions of the lug overlie the sides of the slot as well as the end of the slot. The lug cannot be pulled through the slot without changing the shape of the metal forming the lug and thus the ends are joined so that reclosure is practically prohib- 55 ited. 60

Referring more in detail to the drawing, the invention as illustrated is shown as applied to a jar 1. The closure includes a cap 2 and a band 3. The band has the upper edge 65 portion thereof bent inwardly at an angle as indicated at 4. This inwardly projecting portion of the band overlies the cap 2 as clearly shown in Fig. 1. The ends of the band are joined and after the cap is placed on the jar the band is applied and the lower edge portion is turned underneath the ledge on the jar as indicated at 5. The end 6 of the band is provided with a projecting releasing tongue 7. At the base of the tongue 7 is a 70 slot 8 which is completely within the band and this slot is considerably wider than the thickness of the metal forming the band. The other end 9 of the band is provided with a locking lug 10. This locking lug is cut from 75 the metal and is shaped so as to provide a neck portion 11 and a head which is spear-shaped, thus providing projecting wings 12, 12. The wing portions 12, 12 are folded out of the plane of the lug, as indicated in Fig. 80 85 3. This folded spear head is inserted through the opening 8. The width of the opening 8 is sufficient to allow the folded portions to pass through the slot. After the ends have thus been joined and the said ends pulled 90 upon to bring the slot down close against the base of the neck 11, the wing portions of the spear head are turned down into flat parallel 95 relation with the outer face of the tongue 7 as clearly shown in Fig. 4.

These wing portions 12, 12 overlie the side walls of the slot 8 and the spear shaped head of the lug cannot be pulled through the slot. In order to break the band and release the closure the tongue 8 is lifted and the tongue 100

pulling on the spear head will rupture the metal so as to release the ends, the metal may be scored to weaken it and facilitate such rupturing.

5 It will be apparent that the ends of the band cannot be separated so as to remove the closure and then again attached and a re-closure made. This prevents the removing of the band and the tampering of the contents 10 of the jar and then reclosing the same.

It is obvious that minor changes in the details of construction may be made without departing from the spirit of the invention as set forth in the appended claim.

15 Having fully described my invention, what I claim as new and desire to secure by Letters Patent, is:—

20 A jar closure comprising a cap and a band for securing the cap to the jar, one end of the band having a lifting tongue provided with a slot adjacent the base thereof, the other end of said band having a locking lug struck from the metal of the band and having a spear-shaped head projecting in the same direction as the lifting tongue and provided with laterally projecting wings adapted to be bent so that the head may be inserted 25 through the slot and returned to normal position flat against the lifting tongue overlying the side walls of the slot whereby said lifting tongue may be used to lift and pull on said spear head to rupture the metal and separate 30 the ends of the band.

In testimony whereof I affix my signature.
